[57] ABSTRACT

A slurry explosive composition comprising an inorganic oxidizing acid salt, water, a combustible material, a thickner and a sensitizer selected from the group consisting of alkali metal salts of alkylidiphenyl ether disulfonic acid, dimethylalkylbetaines and fatty acid esters of 1-hydroxyethyl-2-alkylimidazoline. The slurry explosive composition can be initiated by a detonator and has an improved storage stability.

10 Claims, No Drawings

SENSITIZED SLURRY EXPLOSIVE COMPOSITION

The present invention relates to a slurry explosive composition capable of being initiated by the detonator and having an improved storage stability, which is compounded with a novel sensitizer.

Conventional slurry explosive compositions are composed of 10-30% by weight of water; a sensitizer of high explosive, such as TNT, trimethylenetrinitramine, etc. or powder of metal, such as aluminum, Mg-Al alloy, ferrosilicon, etc.; an inorganic oxidizing acid salt, such as ammonium nitrate, sodium nitrate, ammonium perchlorate or the like, and a thickener, such as guar gum. However, when a high explosive is used as a sensitizer, there is a danger in the production and in the use of explosive compositions, and the production cost is high. While, when powdery metal, for example, powdery aluminum, is used as a sensitizer, there is a tendency that aluminum reacts with aqueous solutions of ammonium nitrate to decompose the ammonium nitrate, and the resulting explosive composition decomposes during its production and storage.

Moreover, water compounded to the slurry explosive cannot completely dissolve inorganic oxidizing acid salts, for example, ammonium nitrate, at a temperature lower than room temperature, particularly at low temperature. Therefore, the ammonium nitrate is repeatedly crystallized and dissolved due to the temperature change during the storage of the slurry explosive and deposits coarse crystals. Further, the separation of inorganic oxidizing acid salt from sensitizer is accelerated with the lapse of time. As the results, the detonability of the slurry explosive becomes unstable and the low temperature detonability thereof decreases.

In order to obviate these drawbacks of slurry explosives containing high explosive sensitizer or powdery metal sensitizer, various methods for giving sensitivity to a slurry explosive by introducing fine foams into the explosive without adding high explosive sensitizer or powdery metal sensitizer have recently been investigated. For example, in U.S. Pat. No. 3,582,411, the amount of fine foam to be introduced is controlled by varying the production condition. In U.S. Pat. No. 3,507,718, the density (g/cc) of slurry explosive is adjusted to 0.965-1.36 by compounding a foam-introducing agent of porous carbonaceous materials, such as beet pulp, alfalfa, wood fiber, etc. Further, in Japanese Patent Laid Open Specification No. 4,895/72, slurry explosive is sensitized by a mechanical stirring method and a chemical method. For example, slurry explosive is sensitized by introducing foams into the explosive by gas generating agents, such as hydrogen peroxide, N,N'-dinitrosopentamethylenetetramine, sodium borohydride, etc., or by foam-retaining agents, such as phenol-formaldehyde, glass microballoon, etc. However, in any of these methods, the slurry explosives are not sensitized to such an extent that the slurry explosives can be initiated by the detonator, and further drawbacks of the ignitabilities at low temperature and in small diameter are not solved at all. Further, methods for preventing the separation and decomposition of sensitizers, such as TNT and like, contained in a slurry explosive due to the lapse of time, and for improving the detonability of the explosive at low temperature have been investigated. For example, in Japanese Patent Application Publication No. 15,800/71, a small amount of surfactants, such as trimethylalkylammonium chloride,

etc., is compounded to a slurry explosive containing a high explosive sensitizer, such as TNT or the like, whereby the separation of the sensitizer in the slurry explosive is retarded, and the detonability of the explosive is improved at low temperature.

Further, methods, wherein sensitizers other than powdery metal and high explosive are used for preventing the deterioration of low temperature detonability of slurry explosive and the deterioration of detonability of the explosive due to the lapse of time, have been investigated. For example, in Japanese Patent Application Publication No. 34,957/70, a small amount of alkali metal salt of sulfuric acid ester of aliphatic alcohol is compounded to a slurry explosive, whereby the low temperature detonability of the explosive is improved. In Japanese Patent Laid Open Specification No. 1,345/71, a small amount of hydrophobic emulsifier, such as alkali metal salt of straight chain fatty acid, sorbitan ester, aromatic sulfonic acid, alkylamide and the like, is mixed into a slurry explosive, whereby the low temperature detonability of the explosive is improved. In Japanese Patent Application Publication No. 9,118/72, simple proteins and conjugated proteins, such as albumin, globulin, glycoprotein and the like, are mixed to a slurry explosive, whereby the consistency and low temperature detonability of the explosive are improved.

The above described surfactants and proteins serve to improve the dispersions of organic fuel sensitizer, inorganic oxidizing acid salt and combustible material and to improve the consistency of slurry explosive. However, the surfactant and protein are still insufficient in the improvement of ignitability of slurry explosive in small diameter and the slurry explosive cannot be initiated by the detonator only.

The present invention aims to solve the above described drawbacks of conventional slurry explosives.

The inventors have made various investigations in order to produce a slurry explosive which can be initiated by the detonator alone without the use of conventional sensitizers and is free from the deterioration of performances due to the lapse of time, and found out that, when alkali metal salt of alkylidiphenyl ether disulfonic acid, dimethylalkylbetaine or fatty acid salt of 1-hydroxyethyl-2-alkylimidazoline is used as a sensitizer and mixed with an inorganic oxidizing acid salt, such as ammonium nitrate, water, a combustible material and a thickener, the ammonium nitrate is dispersed uniformly in the mixture, formation of coarse crystals of ammonium nitrate is prevented, uniform fine foams are introduced into the mixture, and further the sensitizer co-operates with the thickener to maintain stably the uniform fine foams for a long period of time, whereby a slurry explosive composition capable of being initiated by the detonator only and having a high detonation velocity and further having high performance, which is free from the deterioration of performance due to the lapse of time, can be obtained.

That is, the slurry explosive composition of the present invention comprises an inorganic oxidizing acid salt, water, a combustible material, a thickener and 0.05-5.0% by weight, based on the total amount of the explosive composition, of a novel sensitizer selected from the group consisting of alkali metal salts of alkylidiphenyl ether disulfonic acid, dimethylalkylbetaines and fatty acid salts of 1-hydroxyethyl-2-alkylimidazoline.

The novel sensitizer to be used in the slurry explosive composition of the present invention will be explained in more detail hereinafter.

The alkali metal salts of alkyldiphenyl ether disulfonic acid are compounds having the following general formula:

wherein R₁ represents an alkyl group having 8-24 carbon atoms and M represents an alkali metal, such as sodium, potassium or the like. Among the compounds, sodium dodecyldiphenyl ether disulfonate is preferably used in the present invention.

The dimethylalkylbetaines are compounds having the following general formula:

wherein R₂ represents an alkyl group having 8-24 carbon atoms. Among the compounds, dimethylalkyl(-coconut oil)-betaine is preferably used in the present invention.

The fatty acid salts of 1-hydroxyethyl-2-alkylimidazoline are compounds having the following general formula:

wherein R₃ represents an alkyl group having 8-24 atoms and R₄ represents a hydrogen atom or an alkyl group having 1 or 2 carbon atoms. Among the compounds, 1-hydroxyethyl-2-alkyl(tallow)-imidazoline acetate, 1-hydroxyethyl-2-alkyl(tallow)-imidazoline formate and the like are preferably used in the present invention.

In the present invention, the above described novel sensitizer is used in an amount of 0.05-5.0% by weight, preferably 0.1-3.0% by weight, based on the total amount of the explosive composition.

The inorganic oxidizing acid salt to be used in the present invention includes ammonium, alkali metal and alkaline earth metal salts of inorganic oxidizing acids, such as nitric acid, chloric acid, hypochlorous acid, perchloric acid and the like. The inorganic oxidizing acid salt can be used alone or in admixture.

The thickener to be used in the present invention includes natural and synthetic high polymers, such as guar gum, polyacrylamide and the like. The thickener can be used alone or in admixture.

The combustible material to be used in the present invention includes liquid combustible materials, such as ethylene glycol, and light oil and other fuel oils, and solid combustible materials, such as powdery sulfur,

urea, powdery coal and the like. The combustible material can be used alone or in admixture.

The slurry explosive composition of the present invention need not contain conventional sensitizers, such as high explosives, for example, TNT, trimethylenetrinitramine, pentaerithrite tetranitrate, etc.; powdery metals such as powdery aluminum, powdery Al-Mg alloy, powdery ferrosilicon, etc; and inorganic oxidizing acid salts of nitrogen-containing base, such as monomethylamine nitrate, ethylenediamine nitrate, hydrazinium nitrate, etc. However, these conventional sensitizers may be added to the slurry explosive composition of the present invention in order to improve the explosive strength of the composition.

The slurry explosive composition of the present invention is prepared as follows. An inorganic oxidizing acid salt and, if desired, a water-soluble solid combustible material are dissolved in water at 50°-60°C under stirring in a mixer equipped with a stirrer. Then, a water-insoluble solid combustible material and, if desired, a water-insoluble liquid combustible material are added to the solution at 50°C under stirring. The resulting mixture, while stirring at 50°C, added with an alkali metal salt of alkyldiphenyl ether disulfonic acid and then a thickener impregnated in a liquid combustible material to obtain the slurry explosive composition.

The sensitizing mechanism of the novel sensitizer to be used in the slurry explosive composition of the present invention has not yet been clarified, but it is clear that the sensitizer serves to prevent the deposition of coarse crystals of ammonium nitrate in the explosive composition, to introduce uniform fine forms thereto, and to improve the sensitivity and detonability thereof.

The slurry explosive composition of the present invention has the following performances. That is, slurry explosive compositions which do not contain the novel sensitizer of the present invention cannot be initiated by using a primer even just after the preparation. On the contrary, the slurry explosive composition of the present invention can be initiated by the primer, and can be initiated by the detonator alone in the case when the mixing ratio of the ingredients is properly selected. Further, the detonability of the explosive composition does not substantially decrease even after 3-month storage. Moreover, the explosive composition does not decompose during storage contrary to conventional slurry explosive composition containing aluminum, and is not dangerous due to the absence of high explosive. Therefore, the slurry explosive composition of the present invention can be handled safely and simply and produced inexpensively, and is very useful for industrial purpose.

The following examples are given for the purpose of illustration of this invention and are not intended as limitations thereof.

EXAMPLES 1 to 5 AND COMPARATIVE EXAMPLE

Slurry explosive compositions were prepared according to the compounding recipe as shown in the following Table 1 in the following manner. Ammonium nitrate and urea were dissolved in water at 50°C under stirring in a mixer equipped with a stirrer. Powdery sulfur and sodium dodecyldiphenyl ether disulfonate were added to the solution and then guar gum impregnated in ethylene glycol was added thereto under stirring. The stirring was continued for 3-4 minutes to obtain 5

EXAMPLES 6 to 10

Slurry explosive compositions were prepared according to the compounding recipe as shown in the following Table 2 in the following manner. Ammonium nitrate and urea were dissolved in water at 50°C under stirring in a mixer equipped with a stirrer. Powdery sulfur and dimethylalkyl(coconut oil)-betaine were added to the solution and then guar gum impregnated in ethylene glycol was added thereto under stirring. The stirring was continued for 3-4 minutes to obtain 5 kinds of slurry explosive compositions having different bulk densities and consistencies as shown in Table 2.

The slurry explosive compositions of Examples 6 to 10 containing dimethylalkyl(coconut oil)-betaine had bulk densities of 0.94, 0.81, 0.89, 0.84 and 1.10 just after the preparation, and had a smooth appearance containing uniform fine foams. These explosive compositions charged into iron tubes having a diameter of 35

mm were satisfactorily detonated by the plain detonator or electric detonator alone. In this case, when the explosive compositions were initiated by using 50 g of dynamite, the explosive compositions were detonated at detonation velocities of 3,860, 3,720, 3,740, 4,000 and 3,030 m/s.

It was found from the above obtained results that dimethylalkyl(coconut oil)-betaine is effective for improving the sensitivity and detonability of a slurry explosive composition even when a very small amount, i.e., 0.05% by weight of dimethylalkyl(coconut oil)-betaine was contained in the explosive composition, and that, when 1-5% by weight of dimethylalkyl(coconut oil)-betaine was contained in a slurry explosive composition, the explosive composition was sensitized to such an extent that the explosive composition can be initiated by the plain detonator or electric detonator alone, and further the detonation velocity of the explosive composition was improved.

mm were completely detonated by the plain detonator or electric detonator alone at detonation velocities (m/s) as shown in Table 2. In this case, when the explosive compositions were initiated by using 50 g of dynamite as a primer, the explosive compositions were detonated at detonation velocities (m/s) as shown in Table 2. Even after 3-month storage, the appearances of the explosive compositions did not change, coarse crystals of ammonium nitrate did not form, and the bulk densities of the explosive compositions did not substantially increase. After 3-month storage, the explosive compositions charged into iron tubes having a diameter of 35

EXAMPLES 11 to 15

Slurry explosive compositions were prepared according to the compounding recipe as shown in the following Table 3 in the following manner. Ammonium nitrate and urea were dissolved in water at 50°C under stirring in a mixer equipped with a stirrer. Powdery sulfur and 1-hydroxyethyl-2-alkyl(tallow)-imidazoline acetate were added to the solution and then guar gum impregnated in ethylene glycol was added thereto under stirring. The stirring was continued for 3-4 minutes to obtain 5 kinds of slurry explosive compositions having

kinds of slurry explosive compositions having different bulk densities and consistencies as shown in Table 1.

The slurry explosive compositions of Examples 1 to 5 containing sodium dodecyldiphenyl ether disulfonate had bulk densities of 0.90, 0.85, 0.87, 0.80 and 1.12 just after the preparation, and had a smooth appearance containing uniform fine foams. These explosive compositions charged into iron tubes having a diameter of 35 mm were completely detonated by the plain detonator or electric detonator alone at detonation velocities (m/s) as shown in Table 1. In this case, when the explosive compositions were initiated by using 50 g of dynamite as a primer, the explosive compositions were detonated at detonation velocities (m/s) as shown in Table 1. Even after 3-month storage, the appearances of the explosive compositions did not change and coarse crystals of ammonium nitrate did not form. Although the bulk densities of the explosive compositions increased to 0.92, 0.88, 0.88, 0.85 and 1.15 after 3-month storage, the explosive compositions charged into iron tubes having a diameter of 35 mm were satisfactorily detonated by the plain detonator or electric detonator alone. In this case, when the explosive compositions were initiated by using 50 g of dynamite, the explosive compositions were detonated at detonation velocities of 3,630, 3,860, 4,160, 3,650 and 2,570 m/s.

It was found from the above obtained results that sodium dodecyldiphenyl ether disulfonate is effective for improving the sensitivity and detonability of a slurry explosive composition even when a very small amount, i.e., 0.05% by weight of sodium dodecyldiphenyl ether disulfonate was contained in the explosive composition, and the explosive composition was detonated at a detonation velocity of 2,930 m/s in an iron tube diameter of 125 mm by the primer initiation. Further, it was found that, when 1-5% by weight of sodium dodecyldiphenyl ether disulfonate was contained in a slurry explosive composition, the explosive composition was sensitized to such an extent that the explosive composi-

tion can be initiated by the plain detonator or electric detonator alone, and further the detonation velocity of the explosive composition was improved.

On the contrary, the slurry explosive composition of the Comparative Example had a bulk density of 1.27 just after the preparation, and had not an appearance containing fine foams. This explosive composition charged into an iron tube having a diameter of 35 mm was not detonated not only in the initiation by the plain detonator or electric detonator alone, but also in the initiation by using 50 g of dynamite as a primer. After 3-month storage, the appearance of the explosive composition did not change, but coarse crystals of ammonium nitrate were observed in the interior of the composition, and the bulk density of the composition increased to 1.37. The explosive composition charged into an iron tube having a diameter of 35 mm was not detonated even when the composition was initiated by using 50 g of dynamite as a primer.

Conventional sensitizers, TNT, powdery aluminum and monomethylamine nitrate, were used in place of sodium dodecyldiphenyl ether disulfonate of the present invention, and slurry explosive compositions containing 5% by weight of the conventional sensitizer were prepared in the same recipe as described in Example 3, and the detonation velocities (m/s) of the explosive compositions in the case when explosive compositions were initiated at 25°C in an iron tube with a diameter of 35 mm by using a plain detonator or an electric detonator together with 50 g of dynamite as a primer, were measured. However, it was found that, even when a conventional sensitizer, TNT, powdery aluminum or monomethylamine nitrate, was added to a slurry explosive composition in an amount as high as 5% by weight, the sensitivity of the resulting slurry explosive compositions was not improved, and the explosive strength of the compositions at the detonation was merely improved.

imidazoline acetate had bulk densities of 0.92, 0.86, 0.91, 0.86 and 1.20 just after the preparation, and had a smooth appearance containing uniform fine foams. These explosive compositions charged into iron tubes having a diameter of 35 mm were completely detonated by the plain detonator or electric detonator alone at detonation velocities (m/s) as shown in Table 3. In this case, when the explosive compositions were initiated by using 50 g of dynamite as a primer, the explosive compositions were detonated at detonation velocities (m/s) as shown in Table 3. Even after 3-month storage, the appearances of the explosive compositions did not change, and coarse crystals of ammonium nitrate did not form. Although the bulk densities of the explosive compositions increased to 0.95, 0.90, 0.96, 0.88 and 1.25 after 3-month storage, the explosive compositions charged into iron tubes having a diameter of 35 mm were satisfactorily detonated by the plain detonator or electric detonator alone. In this case, when the explosive compositions were initiated by using 50 g of dynamite, the explosive compositions were detonated at detonation velocities of 3,630, 3,890, 3,920, 3,630 and 2,860 m/s.

It was found from the above obtained results that 1-hydroxyethyl-2-alkyl(tallow)-imidazoline acetate is effective for improving the sensitivity and detonability of a slurry explosive composition even when a very small amount, i.e., 0.05% by weight of 1-hydroxyethyl-2-alkyl(tallow)-imidazoline acetate was contained in the explosive composition, and the explosive composition was detonated at a detonation velocity of 3,300 m/s in an iron tube diameter of 125 mm by the primer initiation. Further, it was found that, when 1-5% by weight of 1-hydroxyethyl-2-alkyl(tallow)-imidazoline acetate was contained in a slurry explosive composition, the explosive composition was sensitized to such an extent

What is claimed is:

1. A slurry explosive composition comprising an inor-

ganic oxidizing acid salt, water, a combustible material selected from the group consisting of liquid or powdered organic combustible materials and powdered inorganic combustible materials, a thickener and a sensitizer selected from the group consisting of

1. alkali metal salts of alkylidiphenyl ether disulfonic acid having the following general formula

wherein R₁ represents an alkyl group having 8-24 carbon atoms and M represents an alkali metal,

2. dimethylalkylbetaines having the following general formula

wherein R_2 represents an alkyl group having 8-24 carbon atoms, and

3. fatty acid salts of 1-hydroxyethyl-2-alkylimidazoline having the following general formula

wherein R_3 represents an alkyl group having 8-24 carbon atoms and R_4 represents a hydrogen atom or an alkyl group having 1 or 2 carbon atoms.

2. The explosive composition according to claim 1, wherein the amount of said sensitizer is 0.05-5.0% by weight based on the total amount of the explosive composition.

3. The explosive composition according to claim 1, wherein the amount of said sensitizer is 0.1-3.0% by weight based on the total amount of the explosive composition.

4. The explosive composition according to claim 1, wherein said alkali metal salt of alkyldiphenyl ether disulfonic acid is sodium dodecyldiphenyl ether disulfonate.

5. The explosive composition according to claim 1, wherein said dimethylalkylbetaine is dimethylalkyl(-coconut oil)-betaine.

6. The explosive composition according to claim 1, wherein said fatty acid salt of 1-hydroxyethyl-2-

alkylimidazoline is 1-hydroxyethyl-2-alkyl(tallow)-imidazoline acetate or 1-hydroxyethyl-2-alkyl(tallow)-imidazoline formate.

7. The explosive composition according to claim 1, wherein said inorganic oxidizing acid salt includes ammonium, alkali metal and alkaline earth metal salts of nitric acid, chloric acid, hypochlorous acid and perchloric acid and mixtures thereof.

8. The explosive composition according to claim 1, wherein said combustible material comprises a combustible material selected from the group consisting of: ethylene glycol, light oil, fuel oils, powdery sulfur, urea, powdery coal, and mixtures thereof.

9. The explosive composition according to claim 1, wherein said thickener comprises a natural or synthetic high polymers.

10. The explosive composition according to claim 9, wherein said thickener comprises a material selected from the group consisting of guar gum, polyacrylamide and mixtures thereof.
